(57) **CLAIM**

The ornamental design for India ink container, marking tool, as shown and described.

DESCRIPTION

FIG. 1 is a front elevational view of India ink container, marking tool embodying my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a top rear perspective view thereof;

FIG. 8 is bottom rear perspective view thereof;

FIG. 9 is a bottom front perspective view thereof;

FIG. 10 is a top front perspective view thereof;

FIG. 11 is a perspective view thereof showing the outside of the case opened;

FIG. 12 is top rear perspective view thereof showing the case closed with a pin mounted on the case; and,

FIG. 13 is another perspective view thereof showing a state of use.

The broken line showing of an added pin, a cord and a cross section of a horizontal board or material being measured are included for the purpose of illustrating environment and form no part of the claimed design.
